Atty.

UNITED STATES PATENT OFFICE.

LANSING ONDERDONK, OF WINTHROP, MASSACHUSETTS, ASSIGNOR TO UNION SPECIAL SEWING MACHINE COMPANY, OF CHICAGO, ILLINOIS.

LOOPER MECHANISM FOR SEWING-MACHINES.

SPECIFICATION forming part of Letters Patent No. 675,789, dated June 4, 1901.

Application filed November 23, 1896. Serial No. 613,174. (No model.)

To all whom it may concern:

Be it known that I, LANSING ONDERDONK, a citizen of the United States, residing at Winthrop, in the county of Suffolk, State of Massachusetts, have invented certain new and useful Improvements in Sewing-Machines, of which the following is a description, reference being had to the accompanying drawings, and to the figures of reference marked thereon.

My invention relates to an improvement in sewing-machines, and particularly to mechanism for supporting and operating the looper which causes the under thread to coöperate with the needle-thread to form a double chain-stitch.

In an application filed of even date herewith, Serial No. 613,173, which was forfeited and a renewal application thereupon filed September 21, 1900, Serial No. 30,720, I have shown, described, and claimed a construction in which an inclined crank-pin gives oscillatory movement to the looper-carrier in a manner known in the art, the looper-carrier being supported on a pivoted yoke, which in said application is illustrated as fulcrumed on the said driving-pin and derives its motion by any suitable connecting means operated from the main shaft.

The present device in so far as the means for operating the looper-carrier and for oscillating the pivoted yoke supporting the same are concerned may be of any desired construction—for instance, as shown in the aforesaid application; but the invention differs in various detail therefrom, which will be hereinafter described and referred to in the appended claims.

In the accompanying drawings, Figure 1 represents a side view, partly in section, of a portion of a sewing-machine embodying my invention. Fig. 2 is a side view of a portion of the inclined crank with the looper-carrier in section. Figs. 3 and 4 are details of parts of the apparatus going to make up my invention. Fig. 5 is a detail front view of the yoke.

In the drawings the driving-shaft of the machine is shown at 1, and carries forward of its front or outer bearing the inclined or bent pin 2, forming a crank which engages the

forwardly-projecting wings or flanges 3 on the looper-carrier 4, which looper-carrier is pivoted on a yoke 8, having a downwardly-extending arm 24, engaging freely, by means of a sliding pivot connection 5, a frame 17, 55 which is suitably pivoted in the frame of the machine and is oscillated by means of a fork connection 6, which embraces an eccentric 7 on the driving-shaft. Instead of, as in the application mentioned, fulcruming the yoke 60 on the driving-shaft directly, I dispense with the sleeve in the yoke, which is desirable under such circumstances, and provide a stud or short shaft 9, which runs transversely through the looper-carrier and through which 65 stud or shaft passes the bent pin or crank, the said stud or shaft therefore supporting the looper-carrier, and consequently the yoke attached thereto, upon the driving-pin. This stud or shaft 9 is pivoted on the driving-pin 70 and admits of a swinging movement on the driving-pin and also admits of the driving-pin turning or revolving in it and is supported by cone-studs on the yoke 8.

In the rotation of the driving-shaft the bent 75 pin oscillates the looper-carrier 4, which swings on the stud or shaft 9, while in the oscillating movement of the yoke 8 the said stud or shaft 9 oscillates on the driving-pin, thus allowing for the sidewise movement of 80 the looper.

At the forward end the opening 10 in the stud or shaft 9, through which the driving-pin passes, is enlarged or beveled outwardly at a little more of an angle than the angle at 85 which the bent portion of the driving-pin extends, thus avoiding any friction or binding during the rotation of the driving-pin.

As the center of the stud or shaft 9 coincides with the center of the driving-pin at 90 the bend, as shown in Fig. 2, it will be seen that the angle of the driving-pin will keep the stud or shaft 9, and therefore the looper-carrier, up to the central point at all times except when the bent end of the pin lies longitudinal with the jaws of the looper-carrier, in which event the looper-carrier may be slid back, thus preventing revolution of the driving-pin.

Having thus described my invention, what 100

I claim, and desire to secure by Letters Patent, is—

1. In a sewing-machine, a looper-actuating shaft, a yoke with means for oscillating it, a stud or shaft supported on said yoke, and pivoted on the actuating-shaft, a looper-carrier pivotally supported on said stud or shaft, and means for oscillating the looper-carrier, substantially as described.
2. In a sewing-machine in combination with the actuating-shaft, an inclined driving-pin carried thereby, an oscillating yoke connected with the actuating-shaft, a shaft or stud carried by said oscillating yoke and pivoted on the driving-pin; and a looper-carrier pivotally

attached to said stud or shaft, substantially as described.

3. In the herein-described machine, the yoke; means for oscillating it, the driving-pin, the shaft or stud pivoted on said driving-pin and supported in the yoke, a looper-carrier sleeved on said shaft or stud and operatively engaging the driving-pin; substantially as described.

In testimony whereof I affix my signature in presence of two witnesses.

LANSING ONDERDONK.
